UNITED STATES PATENT OFFICE.

LEWIS E. MILLER, OF NEODESHA, KANSAS, ASSIGNOR OF ONE-HALF TO JOHN MORTON MILLER, OF GOODLAND, KANSAS.

1,105,092.

Specification of Letters Patent.

Patented July 28, 1914.

Application filed November 18, 1913. Serial No. 801,715.

To all whom it may concern:

Be it known that I, LEWIS E. MILLER, a citizen of the United States, residing at Neodesha, in the county of Wilson and State of Kansas, have invented a new and useful Egg-Carrier, of which the following is a specification.

The present invention appertains to egg carriers or holders, and aims to provide a novel and improved device of that character.

It is the object of the present invention to provide a unique egg carrier or holder, which will contain the eggs therein in such a manner, that they will be exposed to view, for purpose of examination, but without the possibility of withdrawing or removing any of the eggs without opening the carrier or holder.

Another object of the present invention is to provide a device of the nature indicated which will hold the eggs between opaque sheets having openings or apertures to receive the ends of the eggs, the carrier or holder being open, in order that the same may be applied to a candler or tester, for examining the eggs in toto, to permit unfertile or defective eggs to be marked or removed. A further object of the present invention is to provide a carrier adapted for transmission by parcel post, express or freight, without the liability of injuring the eggs through jostling or handling the carrier.

It is also within the scope of the present invention to provide an egg carrier or holder which shall be comparatively simple, compact and inexpensive in construction, as well as being simple, efficient, practical and convenient in its use.

With the foregoing general objects outlined, and with other objects in view, which will be apparent as the nature of the invention is better understood, the present invention resides in the combination and arrangement of parts and in the details of construction hereinafter described and claimed, it being understood that changes in the precise embodiment of the invention herein disclosed, can be made within the scope of what is claimed, without departing from the spirit of the invention.

The invention has been illustrated in its preferred embodiment in the accompanying drawing, wherein:

Figure 1 is a plan view of the carrier in open or unfolded position. Fig. 2 is a lat-

eral section of the carrier in closed or folded condition, and as applied to a candler or tester. Fig. 3 is a longitudinal section of the carrier in closed position.

The present carrier or tray has been designated generally by the numeral 1, and the candler or tester has been designated generally by the numeral 2.

In carrying out the present invention, the carrier or tray 1 embodies two open sections 3, which are hinged together at one side, as at 4, the other sides of the frames or sections being provided with means for locking or sealing the frames or sections together, as at 5. The sections or frames 3 are rectangular, and at their remote edges, are provided with the inturned flanges 6.

Within each section or frame 3, is slidably disposed a plate or sheet 7 of suitable metal, which is provided with a plurality of apertures or openings 8 of suitable number and arrangement. To the adjoining or inner faces of the plates 7, are attached, by means of cement, or otherwise, paper or cardboard sheets 9, which are provided with apertures 10 or openings 10 registering with but smaller in diameter than the openings 8 of the plates 7, so as to provide flexible lips about the openings 8. The openings 10 are designed to receive the ends of the eggs and are of smaller diameter than the greatest diameters of the eggs, in order that when the eggs are received between the sheets or plates, they will be locked against withdrawal through the openings, although the ends of the eggs will be exposed. The edge portions of the openings 10 are flexible, in order to yield under the pressure of the eggs, to prevent the eggs from being broken or injured by the metallic plates 7, it being understood that if the sheets 9 are of sufficient rigidity, they may be employed exclusive of the plates 7.

The perforated sheets are limited in outward movement, by the flanges 6, and are limited in inward movement by means of the lugs 11 projecting inwardly from the sections or frames 3 adjoining their inner or meeting edges.

The perforated sheets are yieldingly pressed inward, by means of coiled wire springs 12 secured within the corners of the sections or frames 3 adjoining the flanges 6, said springs having terminal arms 13 engaging the remote or outer sides or faces 110

of the perforated sheets. The spring arms 13 bearing against the remote faces of the sheets, will tend to press the sheets together or toward each other.

5 To place the eggs within the carrier or tray, the carrier sections are swung apart or opened, as seen in Fig. 1, and the eggs may then be readily placed upon one of the perforated sheets, the respective ends of the 10 eggs being inserted within the openings or apertures 10. The sections or frames 3 may then be swung together, in order that the other perforated sheet will engage over the respective ends of the eggs, the perforated 15 sheets yielding to accommodate the eggs and to hold them firmly in position. The carrier or tray may then be sealed or locked, as at 5, which will render it impossible to withdraw the eggs from the carrier, unless 20 the seal or lock is broken, and although the eggs are exposed to view for purpose of examination.

A number of the carriers or trays may be 25 crated or boxed for shipping, or a single carrier or tray may be readily transported or shipped. The perforated sheets in yieldingly holding the eggs in place, will permit the eggs to vibrate when the carrier is jostled or handled, without breaking the 30 eggs, it being noted in this connection, that the flexible edge portions of the openings 10 will also eliminate injury to the eggs.

Another important advantage of the present carrier, resides in the fact that the same 35 when containing the eggs, may be applied to a candler or tester, in order that the eggs may be examined in toto to detect any unfertile eggs. To this end, there is conveniently employed, a candler 2, embodying 40 a casing 14 having its top open, and having a mirror or reflector 15 upon its bottom, the casing 14 having a sight opening 16 at one side through which vision is permitted to the observer or examiner. The 45 carrier may be readily inserted upon the casing 14 of the candler, and a suitable lamp or source of light 17 is disposed above the carrier or holder, to illuminate the eggs from above, while the observer may examine

the eggs from below, through the medium 50 of the opening 16 and mirror or reflector 15, as will be apparent. Any unfertile eggs may quickly be detected and marked or removed, it being apparent that the eggs need not be removed from the tray or carrier 55 when undergoing the candling test.

It will be understood that the carrier or holder may also be applied to various other canders or testers and is otherwise of advantage.

60 One of the perforated plates 7—9 is preferably provided with partitions 20, which are of advantage, as is obvious.

Having thus described the invention, what 65 is claimed as new is:—

1. An egg carrier embodying sections, a perforated sheet slidable within each section, and means for yieldably sliding each sheet toward the inner edges of the corresponding section.

70 2. An egg carrier embodying a pair of hinged frames, a perforated sheet movable within each frame, and springs carried by the outer edge portions of the frames for pressing the sheets toward the inner edges 75 of the frames.

3. An egg carrier embodying a pair of co-operable frames, stops carried by the adjoining edge portions of the frames, and perforated sheets movable within the frames, and means carried by the frames for yieldably moving the sheets inwardly toward the stops.

4. An egg carrier embodying complementary sections, complementary spring pressed perforated metallic plates movable within the sections, and yieldable sheets attached to the adjacent sides of the aforesaid plates and having perforations registering with and smaller in diameter than the perforations of 85 the aforesaid plates.

80 In testimony that I claim the foregoing as my own, I have hereto affixed my signature in the presence of two witnesses.

LEWIS E. MILLER.
